UNITED STATES PATENT OFFICE.

JAMES DROMMOND SCHOFIELD, OF DALLAS, TEXAS.

SEEDER.

No. 806,503.

Specification of Letters Patent.

Patented Dec. 5, 1905.

Application filed July 3, 1905. Serial No. 268,282.

To all whom it may concern:

Be it known that I, JAMES DROMMOND SCHOFIELD, a citizen of the United States, residing at Dallas, county of Dallas, State of Texas, have invented a certain new and useful Improvement in Seeders; and I declare the following to be a full, clear, and exact description of the invention, such as will enable others skilled in the art to which it pertains to make and use the same, reference being had to the accompanying drawings, which form a part of this specification.

This invention relates to seeders.

It has for its object a seeder which is especially intended for the planting of cotton seed and corn.

In the drawings, Figure 1 is a perspective view. Fig. 2 is a plan view. Fig. 3 is a longitudinal section through the middle of the frame, and Fig. 4 is a perspective of the casting 8 of Fig. 1.

The frame 1 rests upon the axle 2, upon which are mounted driving-wheels 3 and a bevel-gear 4, which meshes with a pinion 5, which turns the bottom plate of the seed-hopper 6. The seed-hopper itself and the pinion connected with it are lifted out of mesh with the wheel 4 by means that will be hereinafter described and which form one part 30 of the invention thereof.

The frame is pivotally connected by a pin 6^a to the tongue 7, and the rear end of the tongue engages through a casting 8, that may be considered a link. The casting is pivoted to a bracket 9 on the under side of the tongue 7. In the casting 8 are formed bearings 10 for a crank shaft or axle 11, the axis of which is pivoted in bearings 12 on the frame 1. The crank-shaft 11 is provided at 40 the projecting end at the right with a latch-lever 13, the latch of which engages with a quadrant 14, mounted on the frame. The oscillation of the crank (which may be produced by oscillating the lever) actuates the casting 8, which simultaneously swings on its own pivot 81 and lifts the rear end of the tongue (the front end of the tongue is meantime substantially held in position by the engagement of the neck-yoke of the horses) and 50 lifts from the ground the front or pilot plow 15 and the furrow opener 16, both of which are attached to the tongue and both of which are provided with the usual vertical and other adjustments for heights, angularity of blade, &c.

An inner frame 18, pivoted to the outer

frame 1 by pivots 19, carries the covering-plows 20. This inner frame is provided with pivots that engage in inclined slots 38 in a third frame 19^a, located within the second 60 frame 18. The third frame 19^a has secured to it the hopper 6 and is provided with saddle-pieces 61, that normally rest on the axle 2. The front end of the inner or third frame 19^a terminates at each side with a plate provided at its upper forward corner with a hook 21, that engages over a ledge on the lower end of the casting 8 and behind a vertical rib that rises on the back edge of the casting and extends from the ledge upward to or nearly to 70 the bearing 10. The plate 21 is provided with the inclined slot 38, hereinbefore mentioned, in which engages the pin 22 from the second frame 18. The frame 18 is provided at its rear with a cross-bar 26, that rises in a path 75 which causes it to engage under a pin 27, that projects from the rear of the hopper. The main frame 1 is provided with foot-rests 7, and the second frame or first inner frame is provided with a foot-rest 32, employed to 80 enable the user to force down the covering-shovels into the ground should it be desired to do so.

In operating this planter a movement of the hand-lever 13 actuates the movable 85 parts to throw them into their operative position from a condition of travel (or transportation when all the parts are out of motion except the traveling wheels) to a condition of use when all the parts are in position for 90 producing their proper results or the reverse. Thus when the lever is thrown forward on the quadrant the pilot-shovel, furrow-opener, and cover-shovels are in a position to cut to the proper depth into the ground or to a 95 depth to which they have been adjusted, and the hopper is in position over the axle with its feed-wheel engaging the pinion-wheel on the axle. If now the handle be swung to bring its free end to the rear, the first result will 100 be to lift the rear end of the tongue, the pilot-shovel, and the furrow-opener, leaving the covering-shovels still in their working position. This movement results in lifting the front end of the inmost frame 19^a, so as to incline it toward the rear of the machine, when the hopper, which is secured thereto, commences to slide backward and out of engagement as regards the pinion 5 with the bevel-gear 4 on the axle. A slightly further movement lifts first the covering-shovels until the 105 bar 26 strikes the projection 27 on the hop- 110

per and lifts the hopper until the gearing is entirely out of contact with the miter-wheel on the axle and the entire planter is now in condition for travel without work. In producing these results no springs are employed, and there are no springs in the entire device except a single spring 34 on the latch.

The various parts are arranged as a system of levers with a quite complex movement using the axle of the vehicle as one primary support and the neck-yoke support for the tongue as another primary support. The frame 1 is supported on the axle and pivoted to the tongue. The casting 8 is pivoted to the tongue and in pivotal connection with the crank 11, which oscillates on its bearings upon the frame 1. The frame 18 is pivoted to the frame 1 and is supported by a pivot to the inner frame 19^a, with which it has a sliding connection by reason of its pivot projecting through a slot in the frame 19^a. It is lifted by the frame 19^a when the end of the frame 19^a is itself lifted by the casting. Nevertheless the connection between the casting and the ends of the frame 19^a is a sliding connection, which permits of the frame 19^a to perform its function of actuating the frame 18 without a corresponding lifting movement of the rear of the frame 19^a and the hopper supported upon it, and the rear of the frame 19^a only swings upward when it is lifted by the engagement of the frame 18 with the hopper.

What I claim is—

1. In a seed-planter, in combination with a main frame mounted on an axle, a tongue pivotally connected thereto and provided behind the pivot with pilot-shovel and covering-shovel, a secondary frame pivotally connected to the first, a third frame having a seed-hopper secured thereto, connected by pivots to the second frame, and by a sliding connection to the rear end of the tongue, substantially as described.
2. In a seed-planter, in combination with a main frame and a tongue pivoted thereto at a point intermediate its inner and outer ends, a secondary frame and a third frame each pivotally connected to the main frame, a seed-hopper supported by said third frame, a casting through which the inner end of the tongue engages and with one face of which it is pivotally connected, a crank-piece engaging through said casting and journaled at its ends in the main frame whereby said casting and the inner end of the tongue may be raised or lowered with respect to the main frame, means for locking the same in po-

sition, and an actuating connection between the casting and the hopper, substantially as described.

3. In a seed-planter, in combination with a main frame mounted on wheels, a tongue pivotally connected thereto, means for oscillating the tongue with respect to the main frame, a seed-hopper, and means whereby the same rests on the axle, a sliding connection between said hopper and tongue, and a sliding and pivotal connection between said hopper and main frame, substantially as described.

4. In a seed-planter, in combination with a main frame mounted on wheels, a tongue pivotally connected thereto, means for oscillating the tongue with respect to the main frame, a seed-hopper, adjustable hooked saddles upon said seed-hopper adapted to lock the same to the axle with the gears in mesh, a sliding connection between the hopper and tongue, and a sliding and pivotal connection between the hopper and the main frame, substantially as described.

5. In a seed-planter, in combination with a main frame mounted on an axle, a tongue pivotally connected therewith, a pilot-shovel and a covering-shovel carried thereby, a plurality of subsidiary frames pivotally connected therewith and with each other, and a seed-hopper carried by one of said subsidiary frames, said hopper being slidably connected with the rear end of the tongue, substantially as described.

6. In a seed-planter, in combination with a main frame and a plurality of auxiliary frames pivotally connected therewith, a tongue pivotally connected to said main frame, with one portion extending therewithin, a casting through which said tongue loosely engages, a pivotal connection between one face of the tongue and said casting, a crank engaging through a part of said casting remote from said pivoted connection, means whereby said crank may be raised or lowered, means for locking it in position, a hopper supported by one of said auxiliary frames, and a connection between said hopper and the adjacent end of the tongue, substantially as described.

In testimony whereof I sign this specification in the presence of two witnesses.

JAMES DROMMOND SCHOFIELD.
